INTERIOR TELEPHONE EQUIPMENT

Richard Varley, St. George, Staten Island, N. Y.,
assignor to Inter-Outer Telephone Corporation, Dover, Del., a corporation of Delaware

Application August 31, 1935, Serial No. 38,691

6 Claims. (Cl. 179—81)

My invention relates to interior telephone equipment, and it has special reference to telephone systems in which a French type of telephone instrument, constituting a part of a public telephone system, may be acoustically coupled to a private electrically independent interior telephone equipment, without interfering with or modifying the property or operation of the public telephone system.

At the present time, so-called "hard of hearing" telephone sets have been developed particularly for the individual use of persons who are subject to deafness, and these telephone sets, which embody readily controllable electronic amplifier units for increasing the intensity or volume of speech, as desired, may be leased from the public telephone companies.

Moreover, by arrangement with the public telephone companies, special temporary installations embodying a plurality of ordinary individual telephone sets may be leased for unusual occasions, as when in the conduct of business it may be found desirable and expedient for a group of men, in conference for instance, to be enabled to have multi-party telephone communication over a public telephone system with an outside party or parties located at a distant point.

One of the objects of my present invention is, while furnishing the usual and ordinary telephone service of a public telephone system, to meet the requirements of either of such unusual classes of extraordinary service, as mentioned above, by providing auxiliary equipment which may be readily placed in operative acoustical relation to the telephone instrument of a public telephone system, and which serves to extend the facilities thereof to either an individual subject to deafness or to a group of business men for instance, all of which group may not only hear the incoming conversation, but may take part in the conversation, as though the outside distant party were actually present with the group, and without the necessity or inconvenience of the usual individual telephone instruments.

Another object of my invention is to provide a simple, compact, inexpensive and reliable telephone equipment for either class of special service above referred to, which equipment, by reason of its complete electrical independence of the public telephone system, may be privately owned and operated without continual rentals.

A further object of my invention is to attain the desired service and results mentioned through the use of a coupling device which is adapted, when a French type telephone instrument of a

public telephone system is placed in acoustical relation therewith, to electrically amplify or intensify the incoming messages from the receiver thereof and audibly deliver such messages to the user through either a telephone receiver or a 5 loud-speaker, and which is further adapted through the agency of one or more speaking tubes in conjunction with a sound-directing horn or megaphone acoustically related to the transmitter of the public telephone instrument, to 10 permit one or more parties to talk with an outside distant party in the manner indicated.

These and other objects of my invention and features by means of which these objects are attained will be apparent from the following description of my invention in connection with the single figure of the accompanying drawing which is a diagrammatic view illustrating one convenient form of telephonic equipment embodying my invention.

Referring to the drawing, the invention there-in illustrated comprises a subscriber's telephone set T of a public telephone system having a removable French type telephone instrument F; an auxiliary coupling device C including an electronic amplifier A, one or more flexible speaking tubes ST, a common sound chamber SC there-for and a horn or megaphone M; together with a loud-speaker LS and a sub-base SB for the public telephone set T which embodies therein a suitable control switch CS for automatically connecting the electronic amplifier A to a source of power whenever the French telephone instrument F is removed from its cradle.

The public telephone set T is of the common type and may, or may not, include a dial mechanism, and embodies a base 2 and a cradle 4 upon which the French type telephone instrument F normally rests when not in use. This instrument F, in accordance with usual practice, embodies a transmitter 6 and a receiver 8 which are disposed in fixed relation at the opposite ends of a hand grip 10.

The telephone set T is electrically independent of the rest of the equipment, but, in order to carry out a desirable function of my invention, it normally rests upon a floating platform 12 constituting a part of the sub-base SB. This platform 12 is adapted for vertical movement within the sub-base and is supported by a plurality of springs 14. The control switch CS associated therewith includes a plurality of spring contacts 16 and 18 which are suitably mounted by means of insulating blocks 20 and 22 upon a portion of the stationary sub-base and 55

the floating platform 12, respectively. The spring contacts 16 and 18 are placed in such vertical relation that electrical engagement thereof may be effected when the floating platform is 5 raised by the springs 14 whenever the total weight of the telephone set T is decreased by the removal of the French telephone instrument from its cradle 4. However, when this telephone instrument rests in its cradle, the combined weight is 10 sufficient to lower the floating platform 12 and separate the cooperating spring contacts 16 and 18. These relative movements of the spring contacts are utilized for the purpose of controlling the operation of the electronic amplifier A associated with my coupling device C, as will later become apparent.

The coupling device C embodies a cabinet 26 having an inclined front panel 28 which is provided with an upper opening 30 and a lower 20 opening 32 disposed in substantial vertical alignment and spaced apart a distance corresponding to the fixed spacing of the receiver 8 and transmitter 6 of the French type telephone instrument F. Said telephone instrument F, when 25 placed upon the front panel 28, is suspended by a supporting flange 34, which is preferably semi-circular in form, with the receiver 8 and transmitter 6 in registry with the upper and lower panel openings 30 and 32, respectively.

30 Within the cabinet 26 and positioned immediately in back of the upper opening 30 is a microphone 36, preferably of the two-buttoned type, which is connected in the usual manner by input conductors 38 with the electronic amplifier A.

35 This electronic amplifier A is of conventional construction, including vacuum tubes of the amplifying and rectifying type, choke coils, transformers, condensers and other elements commonly employed in the construction of such devices. A suitable amplifier is typified by the 40 RCA Victor portable sound amplifier—Type P. G.—63, or the Universal amplifier assembly (6 watts) may be employed.

While the particular amplifiers mentioned are 45 adapted to be connected to an alternating current source of power, my invention may be carried out with any other type of amplifier, such, for example, as those which are connected to a direct current source of power or those which 50 are operated by batteries. All such amplifiers, regardless of their type, are provided with means for regulating or adjusting the degree of amplification. This is a desirable adjunct to my invention but, since it is common to all types of 55 amplifiers, it is typified in the drawing only by a simple adjusting knob 40. The amplifier is also provided with the usual power terminals 42 and output terminals 44.

Also mounted within the cabinet 26 is the 60 sound chamber SC and the sound-directing horn or megaphone M, both of which may be of any suitable form or construction. The smaller end of the megaphone is in open communication with the sound chamber SC and its larger end disposed immediately behind and in close proximity to the lower panel opening 32. The sound chamber SC is also provided with a plurality of speaking tubes ST which are preferably flexible in 65 form and which freely communicate at one end 70 with the sound chamber and are provided at their free ends with suitable mouth pieces 46.

The mouth piece 46 of one of the speaking tubes ST constitutes a part of a hand grip instrument F', which carries the mouth piece referred to at one end and which is provided with 75

an ordinary telephone receiver 50 at the other end. At the receiver end of the instrument F' is a supporting member 52 having a suitable opening therein by means of which it may be hung or suspended upon a supporting hook 54 5 conveniently positioned on cabinet 26. The other speaking tubes ST, which may be of any desired number, usually only include the mouth-pieces 46 but may, if desired, have associated therewith hand-grip instruments similar to that 10 shown and described, as denoted by the reference character F'. By reason of the flexible nature of the speaking tubes and the fact that they may be of any desired length, they are adapted for convenient distribution within the 15 room, for instance, at different locations around a conference table.

The loud-speaker LS is also of conventional construction and may be located as desired within the room or, of course, may be contained within the cabinet 26 if so preferred. In either event, it is adapted to be connected by suitable conductors to the output terminals 44 of the electronic amplifier A. For purposes of enabling the adjustment of the connections of the loud-speaker LS and the telephone receiver 50 of the hand grip instrument F', in accordance with whatever character of service is being utilized, a change-over switch 53 associated either within or without the cabinet 26, is provided whereby 30 the user may arrange at will for the operation of either the loud-speaker LS or the telephone receiver 50.

Having described some of the structural features of certain parts of the equipment, the operation and circuit connections thereof will be set forth.

Assuming that the French type telephone instrument F of the public telephone system is resting upon its cradle 4 and a call is received thereon, 40 the instrument is removed from the cradle and may be utilized in the regular conventional manner for telephonic conversation.

However, if the telephone is being used by a 45 person subject to deafness it is only necessary for him to place the French type telephone instrument F upon the inclined panel 28 of the acoustical coupling device C in the manner previously indicated, whereby an acoustical coupling is effected between the interior telephone equipment and the public telephone system which enables a 50 conversation to be conducted through the agency of the auxiliary hand-grip instrument F'.

As a preliminary to such a conversation and in 55 preparation therefor, the removal of the French type instrument F from its cradle decreases the weight of the telephone set T and permits the springs 14 within the sub-base SB to raise the floating platform 12 and establish an electrical 60 engagement between the spring contacts 16 and 18 of the control switch CS. Accordingly, a circuit is established from one side of a source of power marked AC through conductor 56, spring contacts 18 and 16 and conductor 58 to one power 65 terminal 42 of the electronic amplifier A, the circuit being completed from the other terminal thereof through conductor 60 and conductor 62 to the other side of the source of energy. In this way the electronic amplifier A is immediately connected to the source of power whenever the 70 French type telephone instrument F is removed from its cradle, and therefore the energization and usual warming up period of the amplifier tubes is promptly initiated so that the amplifier 75

will be quickly heated to a suitable condition for use.

In order to advise the user that the French telephone instrument F is out of its cradle, an audible or visible signal device 64 is provided and thrown into operation concurrently with the supply of power to the amplifier A at the moment that the French telephone instrument F is removed from its cradle. This is accomplished by connecting signal device 64 from conductor 58 through conductor 66 to conductor 62 which connects with one side of the source of energy, the other side thereof being connected in the manner and by the means previously set forth.

Having effected the acoustical coupling between the French telephone instrument F and the coupling device C in the manner set forth, it will be understood that the incoming call or message emanating from the receiver 8 of the subscriber's instrument F is acoustically picked up by the microphone 36 and delivered to the amplifier A, from which it is relayed at intensified or amplified volume, controllable at the will of the operator by the adjusting knob 40, to the receiver 50 of the hand-grip instrument F'. This is effected through a circuit from one output terminal 44 of the amplifier through conductor 68, switch arm 70 and contact 72 of the control switch 53, conductor 74, receiver 50 of the instrument F', and conductor 76 to the other output terminal of the amplifier. The conductors 74 and 76 may be conveniently disposed within the speaking tube ST associated with the hand-grip instrument F'.

By this means the user may utilize the instrument F' to receive, at controllable amplified volume, the messages or call delivered acoustically by the receiver 8 of subscriber's telephone instrument to the interior telephone equipment.

On the other hand, the user may talk with the outside party by merely speaking into the mouth-piece 46 associated with the hand-grip instrument F', the sound or speech being carried through the speaking tube ST, sound chamber SC and sound-directing megaphone horn M in a well understood manner, from which it is transmitted acoustically to the transmitter 6 of the public French telephone instrument F.

As soon as the conversation has terminated, the auxiliary hand-grip instrument F' is hung up on its supporting hook 54 and the French type telephone instrument F restored to its cradle, whereupon the increased weight of the telephone set T depresses the floating platform 12 and interrupts the electrical circuit supplying energy to the signal device 64 and the electronic amplifier A. Should the user neglect to restore the telephone instrument F, the signal device 64 continues to operate until such action has been taken.

Of course, if this interior telephone equipment is intended merely for the use of a person subject to deafness, it is unnecessary to equip it with more than the single speaking tube already referred to as connected to the handgrip instrument F'.

Turning now to the other type of service of my invention, namely, for purposes of multi-party conversation over the public telephone system between a group of individuals, around a conference table for instance, with an outside party at some distant point, a plurality of speaking tubes 46 is utilized, as before suggested. For such service the incoming messages are received over the loudspeaker LS by means of which the messages are delivered into the room and may be heard by all occupants thereof. In order to render the loudspeaker LS operable, it is only neces-

sary to operate the control switch 53 to cause its switch arm 70 to engage contact member 78. In this way, one output terminal 44 of the electronic amplifier A is connected to the loud-speaker by means of conductor 68, switch arm 70 and contact member 78 of the control switch 53 and conductor 80, while the other output terminal 44 of the amplifier is connected to the loud-speaker by means of conductor 82.

Without further description it will be understood that, by providing the various individuals of the conference group with separate speaking tubes ST, it is possible for any and all of the members of the group to enter the conversation and talk with the distant party just as though he were personally present and conversing with them.

Although I have described my invention as embodying more or less specific details of construction, arrangement and location of parts and circuit connections and operation, it will be understood that many modifications may be made therein without departing from the spirit and scope of my invention, and therefore only such limitations should be imposed as are indicated in the appended claims.

I claim as my invention:

1. The combination of a subscriber's public telephone set having a transmitter and a receiver, electrical means electrically independent of said telephone set and including a loud-speaker, an auxiliary receiver, switching means for selectively operating the one or the other and circuit connections therefor for acoustically picking up sound waves from the receiver of said telephone set and delivering them at intensified volume to either said loudspeaker or said auxiliary telephone receiver, mechanical means including a flexible speaking tube having a mouth piece at its free end and a megaphone at the other end thereof for acoustically delivering sound waves produced by speech to the transmitter of said telephone set, and a hand grip device with which said auxiliary receiver and the mouth piece of said speaking tube are associated in fixed spaced relation, the circuit connections for said auxiliary telephone receiver being disposed within said speaking tube.

2. A unitary telephonic device adapted to be acoustically coupled to the transmitter and receiver of a public telephone set, but electrically independent thereof, comprising in combination, a cabinet having in one of its walls a pair of openings with which the receiver and transmitter of said public telephone set may be placed in registry, a microphone mounted immediately behind and in registry with one of said wall openings, an electronic amplifier and sound-producing means electrically connected to said microphone, one or more speaking tubes and a sound-directing megaphone operatively associated therewith and having its larger end disposed immediately behind and in registry with the other of said wall openings.

3. A unitary telephonic device adapted to be acoustically coupled to a French type telephone instrument of a public telephone system but electrically independent thereof, comprising in combination, a cabinet having openings in one of its walls so spaced as to correspond to the spacing of the transmitter and receiver of said French type telephone instrument, a microphone disposed immediately behind and in registry with one of said wall openings, an electronic amplifier electrically connected thereto, electrical sound-producing means operably connected to said ampli-

- 5 flier, a sound-directing megaphone having its larger end disposed immediately behind and in registry with the other of said wall openings, one or more speaking tubes operably associated with said megaphone, and means adapted to support a French type telephone instrument with its receiver and transmitter in registry with said wall openings.
4. The combination of a subscriber's public 10 telephone set having a transmitter and a receiver, a loud speaker, an auxiliary receiver, switching means for selectively operating the one or the other and circuit connections therefor, and electrical means electrically independent of said telephone set for acoustically picking up sound waves from the receiver of said telephone set and delivering them at intensified volume to either said loud speaker or said auxiliary telephone receiver, and mechanical means including a flexible speaking 15 tube having a mouthpiece at its free end and sound directing means at the other end disposed adjacent the transmitter of said telephone set for acoustically delivering to said transmitter of said telephone set sound waves produced by speech 20 into said mouthpiece.
5. A unitary telephonic device adapted to be 25 acoustically coupled to a French type telephone instrument of a public telephone system but electrically independent thereof, comprising in combination, a cabinet having openings in one of its walls so spaced as to correspond to the spacing of the transmitter and receiver of said French type telephone instrument, a microphone disposed adjacent one of said openings, a speaking tube hav-
- ing a mouthpiece at its free end and its other end terminating adjacent the other of said openings, an electronic amplifier connected to said microphone, an auxiliary receiver and a loud speaker, and selective means for connecting either said auxiliary receiver or said loud speaker to said electronic amplifier.
6. A unitary device adapted to be acoustically coupled to a French type of telephone instrument of a public telephone system but electrically independent thereof, comprising in combination, a cabinet having an inclined front panel provided with a pair of openings in substantial vertical alignment and so spaced as to register with the transmitter and receiver of said French telephone instrument, means for supporting the French telephone instrument from its upper end so that its transmitter and receiver overlie said panel openings in substantially vertical operative positions, a microphone disposed in proximity to one of said openings in acoustical relation to the receiver of said telephone instrument, an electronic amplifier connected to said microphone, a sound producing device connected to said amplifier; a flexible speaking tube having a mouthpiece to receive speech and a sound directing megaphone having its smaller end operatively associated with said speaking tube and positioned within said cabinet with its larger end in proximity to said other panel opening and in acoustical relation with the transmitter of said French telephone instrument.

RICHARD VARLEY.
